UNITED STATES PATENT OFFICE

JAMES H. MOLLOY, OF CHICAGO, ILLINOIS, ASSIGNOR TO THE RAILROAD SUPPLY COMPANY, OF CHICAGO, ILLINOIS, A CORPORATION OF ILLINOIS

AUXILIARY BASE FOR SIGNAL AND CABLE POSTS

Application filed May 2, 1927. Serial No. 188,391.

This invention relates to new and useful improvements in auxiliary bases for signal and cable posts.

The device serves the double function of providing an auxiliary base for a conventional signal post and a chamber wherein a plurality of circuit wires, connected with a source of power, and circuit wires leading to the signal, as well as to other electrical devices, not necessarily associated with the signal, may be conveniently connected as desired. Heretofore signal posts have been mounted directly upon a concrete foundation and the circuit wires led from a source of supply to a junction box located adjacent to the foundation or to the signal post, but not a part thereof. These arrangements have been undesirable in that the junction boxes are unsightly in appearance and their location has subjected the circuit wires to undue exposure.

The object of this invention is to produce a construction which, when used with a foundation and signal post, will form a unitary structure, which will serve as a junction box for the circuit wires, and have suitable openings for the incoming and outgoing wires, and to render the interior of the device accessible.

Another object of the invention is to provide means for securely closing the said openings so that the interior of the chamber and its contents will be properly protected.

Another object of the invention is to so construct the concrete foundation and the auxiliary base that the circuit wire cable may enter the auxiliary base and the wires be led away from the auxiliary base without being exposed to the elements.

In the drawings:

Figure 1 is a front elevation of an auxiliary base for signal posts embodying my invention, together with a signal post and the concrete foundation, the latter being shown in section.

Figure 2 is a transverse, vertical, sectional view, taken in plane in the line 2—2 of Figure 3, looking in the direction indicated by the arrow.

Figure 3 is a horizontal, sectional view taken in the plane of the line 3—3 of Figure 2,

and looking in the direction indicated by the arrow.

Figure 4 is a transverse, vertical, sectional view taken in the plane of the line 4—4 of Figure 3.

Figure 5 is a horizontal, sectional view of a modified form taken in the plane of the line 5—5 of Figure 6, certain parts of the structure being omitted.

Figure 6 is a front view of the modified form shown in Figure 5.

In the drawings A represents my auxiliary base, as a whole, B is a concrete foundation therefor, and C is a conventional signal post.

The auxiliary base A comprises a metal housing, having vertically extending side walls 1, and horizontal top and bottom, inwardly extending, annular flanges 2 and 3, respectively. The annular flanges 2 and 3 are of such width as to leave a central opening 4 in the top and bottom of the housing A, to accommodate the cable 5 which enters the housing A through the passageway 6 in the concrete foundation B. The central opening 4 in the upper flange 2 permits circuit wires to be led upwardly into the signal post C.

The housing A may be round in horizontal cross section, as shown in Figures 1 to 4, inclusive, or it may be square as shown in Figures 5 and 6. The shape of the housing is immaterial.

The side walls of the housing A are provided with a number of openings, four being shown to render the interior of the housing A accessible, as well as to form one or more outlets for circuit wires or trunking. As shown in Figure 3, three of the wall openings are closed by removable closure plates herein-after to be described. The fourth opening is used as a trunking outlet.

The trunking housing is secured in one of the wall openings. It may be square in cross section as shown, and has flanges 8 complementally shaped to fit against flanges 9 on the wall 1 surrounding the wall openings. A gasket 10 is interposed between the flanges 8 and 9. The trunking housing 7 is securely held in place by set screws 11, in the screw threaded, apertured lugs 12, which are in-

tegral with the flanges 8 of the housing 7. To insert the trunking housing 7 in place, the screws 11 are turned so as to withdraw the ends 13 thereof, and permit the lugs 12 to 5 enter the wall aperture. Then the screws 11 are turned in the opposite direction to bring the ends 13 in contact with the inner wall 1 of the housing A. In this manner the flanges 8 are tightly held against the wall flanges 9 10 and gasket 10.

Referring now to the means for closing the other apertures in the wall 1 of the housing A, 14 indicates an apertured closure plate, strengthened by ribs 14', and having flanges 15 15 complementary to flanges 9 of the wall 1. A gasket 10 is interposed between the flanges 15 and 9. The closure plate 14 may be curved, as shown in Figures 1 to 4, inclusive, or flat, as shown in Figures 5 and 6, depending on the 20 form of housing A with which it may be used. The closure plate 14 is held in position by a screw bolt 16, which extends through the aperture 17 in the closure plate 14, and through the threaded aperture in a retaining 25 bar 18. The retaining bar 18 is held in proper horizontal position by lugs 19 which project from the inner surface of the closure plate 14. By turning the head 20 of the bolt 16, the retaining bar 18 is drawn closer to the closure 30 plate 14 thereby holding the retaining bar 18 closely against the inner surface of the wall 1 and maintaining the flange 15 snugly against the gasket 10 and flange 9 of the wall 1.

It will be noted that the openings in the wall 1, flanged at 9, are identical in size and form, so that one or more may be used as trunking outlets and may have trunking housings secured therein, or may be closed by 40 closure plates 14 as heretofore described.

The flanges 2 and 3 extending from the wall 1, are provided with vertically arranged pairs of lugs 21 between which a terminal board 22 is positioned. The terminal board 22, per se, 45 is not a part of my invention and need not be described in detail. It is provided with conventional terminal plates and binding posts whereby the circuit wires may be conveniently connected as desired.

It will be understood that the bottom flange 3 of the housing A rests upon the concrete base B, the central opening 4 therein registering with the passageway 6 in the concrete 55 B, as heretofore explained. The base plate 23 of a conventional signal post C constitutes a top for the auxiliary base housing A and rests upon the upper flange 2 thereof.

In new installations, I prefer to use relatively long anchor bolts 24, embedded in the concrete B, said anchor bolts being adapted to extend upwardly through apertures 26 in the flanges 2 and 3 of the auxiliary base A, and through apertures in the signal post base 65 23. A nut 25 is provided for the bolts 24, to

hold the base 23 firmly down upon the housing A.

In Figure 6, I have shown a modified method of securing the auxiliary base A between the foundation B and the signal base C. That is to say, instead of using the relatively 70 long anchor bolts 24, I use a number of shorter bolts 27 and nuts 28. This method of attachment is preferably used in repair jobs where the auxiliary base is interposed between an 75 existing signal post and its foundation B.

The modified form shown in Figure 5 need not be described in detail. It differs from that shown in Figure 3 only in that the shape of the housing is square instead of round, and flat closure plates 14 are used in place of 80 curved plates. In this form the bolt holes 26 are elongated.

From the foregoing description, it will be apparent that this device will function efficiently as a junction box for circuit wires and its interposition between the concrete foundation and the conventional signal posts results in a saving of metal in the construction 90 of junction boxes and in providing a desirable 95 method of leading the circuit wires to a signal and to other electric devices not associated with the signal.

While I have herein described the housing 7 with its flanges 8 as a housing for "trunking" 95 (known by those skilled in the art to be a wooden container for loose wires), I desire it to be understood that the housing 7 may serve as a conduit for armored wires and cables as well as a trunking housing.

I claim for my invention:

1. A base for a signal post comprising a housing structure having means for securement to a foundation and also having provision for the mounting of a signal post thereon, with communication between the interior of the housing and the interior of the signal post, said housing structure having openings in its side walls provided with interchangeable outlet fittings and closure plates.

2. A base for a signal post comprising a housing structure having means for securement to a foundation and also having provision for the mounting of a signal post thereon, with communication between the interior of the housing and the interior of the signal post, said housing structure having openings in its side walls provided with interchangeable outlet fittings and closure plates, and means for securing a terminal board in said hollow body.

In testimony that I, claim the foregoing as my invention I affix my signature this 25th day of April, 1927.

JAMES H. MOLLOY.
